WILBUR C. SMITH, OF ST. LOUIS, MISSOURI, ASSIGNOR OF ONE-HALF TO BURDETTE C. LUTZ, OF JEFFERSONVILLE, INDIANA.

TYPE-DISTRIBUTUTING MACHINE.

1,279,470.

Specification of Letters Patent. Patented Sept. 17, 1918.

Original application filed November 3, 1916, Serial No. 129,382. Divided and this application filed April 11, 1917. Serial No. 161,185.

To all whom it may concern:

Be it known that I, WILBUR C. SMITH, a citizen of the United States, residing at the city of St Louis, State of Missouri, have invented a certain new and useful Improvement in Type-Distributing Machines, of which the following is a full, clear, and exact description, such as will enable others skilled in the art to which it appertains to make and use the same, reference being had to the accompanying drawings, forming part of this specification.

This invention relates broadly to printing and specifically to a machine for distributing type from composed form to assorted form. It is of a sort wherein the selection of the type from the composed line, and its differential distribution into assorted divisions is dependent upon the volition of the operator, and the operation of the machine for the handling of the type is rendered effective through the operation of a keyboard mechanism. The invention is particularly adapted to the handling of short grooved type of the sort customarily employed in the machine commercially known as the multigraph, and it is in connection with such use that the invention is herein illustrated and described.

My present application is a division of my prior application filed November 3, 1916, Serial No. 129,382, for type setting and distributing machine, in which application the mechanism herein illustrated and claimed is shown in its co-operative association with the mechanism for setting the type into composed form.

As is well known in the art in printing from individually movable type, it is necessary to go through a process of selection and assembly to make the suitable composition, and then to go through a process of selection and distribution from type in composed form in order that the type may be properly assorted and made rapidly accessible for subsequent composition.

In present practice, the familiar use of type of the sort described is made in the machine commercially known as the multi-

graph which is designed for operation and use in business offices or establishments not devoted primarily to the business of printing. Type commonly employed in such machines is quite short and not readily manipulated by hand. The broad purpose of my invention, consequently, is to provide a machine capable of rapid and facile operation whereby type which is assembled in composed form may be distributed directly from the printing device into suitable supply or magazine compartments in proper position for subsequent setting operations.

Another object is to provide such a machine wherein the amount of mechanical handling or contact to which the type is subjected is reduced to a minimum, and thereby the possibility of injury to the type is largely obviated.

A further object of the invention is to provide a mechanism of the sort specified which is operable through a keyboard arrangement conforming to the standard typewriter keyboard arrangement, by virtue of which provision the machine is susceptible of accurate and rapid operation by an operator practised in typewriting.

Other objects reside in the provision of the several mechanisms for the several operations and purposes hereinafter described, and other and further objects will be obvious or pointed out hereinafter.

In general, the machine comprises means whereby the types are selectively released, one at a time, from a compartment in which they are held in their composed form, and are conveyed and guided in the proper order into selectively differentiated positions, whence they are moved and deposited in proper position in suitable magazine compartments from which they subsequently may be mechanically selected for composition. The operation of selecting the type from the composed line, differentially positioning them, and depositing them in the magazine compartments, are all effected through operation of a keyboard having its several elements identified with the several type characters to be handled.

In the accompanying drawings, I have shown, for the purpose of illustration, one embodiment of my invention, the same comprising a machine designed for the distributing of short grooved type.

In these drawings, Figure 1 represents a vertical sectional view taken longitudinally through the lower portion of the machine and showing representative elements of the keyboard mechanism and their associated parts;

Fig. 2 is a detail illustrating a part of the same in an altered position;

Fig. 3 is a detail illustrating a side view 15 of a portion of the machine hereinafter referred to as the distributing column;

Fig. 4 is a detail illustrating the upper portion of the distributing column and particularly the upper and lower case switching 20 device;

Fig. 5 is a perspective illustrating the upper and lower case switching guides at the upper end of the distributing column;

Fig. 6 is a perspective illustrating the 25 switching valve for the upper and lower case distribution;

Fig. 7 is a detail illustrating the case shift-key mechanism;

Fig. 8 is a transverse sectional elevation 30 of the upper portion of the distributing column showing the association of the printing segment and the magazine therewith;

Fig. 9 is a cross section of the distributing column;

Fig. 10 is a fragmentary perspective illustrating the distributing guides and an associated selecting valve.

Referring to the illustrations by the characters of reference, let it be understood that 40 a suitable casing or frame is arranged to support and house the various portions of the mechanism, and upon which frame is mounted a shiftable keyboard frame 2 which is movable forwardly and rearwardly to 45 selective positions for the purpose hereinafter described. This shiftable keyboard frame carries the manually operable key members 4 the levers of which coöperate with a universal bar 5.

50 The distributing mechanism may be arbitrarily subdivided into three parts, first a separating mechanism, second an assorting mechanism, and third, a type-depositing mechanism. The separating mechanism will be best understood by reference to Figs. 4 and 8. At the top of the machine means is provided for mounting the printing cylinder S resting on its right hand end and with its type grooves extending vertically.

60 The arrangement of the cylinder is such that its type grooves may be turned to aline with a groove formed by guide members 85 (see Figs. 3 and 8) into which latter groove type from the alined slot of the printing cylinder

will feed by gravity. The feed of type 65 along the guide members 85 is controlled by a separating valve 86. This valve 86 is operable by means hereinafter to be described, to separate and release type fed downwardly from the printing cylinder, 70 one at a time, to permit their proceeding into the separating channel 87. This valve is carried in a slideway on the frame and is formed with a slot 86^a of size sufficient to permit the passage of a type sidewise there- 75 through. Extending longitudinally over a portion of this slot is a separating finger 86^b, which finger extends in the direction in which the valve is moved to release a type. The valve is spring pressed so as to 80 normally occupy a position across the slot formed by the guide members 85, thereby acting as a retaining member which supports the superadjacent column of type. The lower extremities of the members 85 85 pass through the slot of the valve and maintain the unbroken continuity of the parts upon which the slotted portions of the type travel. The separating finger 86^b is spaced apart above the type-supporting portion of 90 the valve by a distance just sufficient to accommodate the width of a type, and the forward extremity of the separating finger 86^b lies to the rear of the forward edge of the slot 86^a by a distance somewhat less than 95 the length of a type. Consequently, when the valve is moved forward to release the lowermost type, which rests thereon while being retained by the guide members 85, the separating finger 86^b will be moved under 100 the next superadjacent type so that by the time the lowermost type is released to fall through the slot 86^a, the column of type thereabove will be supported on the separating finger 86^b. When the valve is re- 105 turned under pressure of its spring, the portion forming the forward edge of the slot 86^a will be interposed below the column of type before the latter is released from the separating finger 86^b. In this fashion, the 110 types are separated one at a time from the composed line in the printing cylinder or segment.

The types travel down the guides 85 with the right hand sides down, and with their 115 top and bottom slots riding on the guides 85. The lower extremities of the guides 85 terminate short of the lower sloping side of the assorting channel 87, so that, when the type is deposited in the channel, it is freed 120 from the guides 85, and allowed to slide down the channel rear end first. Shortly below the terminus of the guides 85, the assorting channel 87 divides (see Figs. 4 and 5) into an upper case assorting channel 88 125 and a lower case assorting channel 89, the former branching toward the front and the latter toward the rear of the machine. The

feed of type into these channels is controlled by a case switching valve 90. This switching valve 90 is shiftable across the channels 88 and 89, and has a block portion 5 90^a adapted to close either channel selectively, and to form a wall portion of the unclosed channel. The valve 90 is provided with apertures 90^b, one at each side of the block member 90^a, which apertures are 10 adapted to register with the respective channels, when they are open, so as to permit the feed of type past the switching member. By the proper setting of this switching member, which is accomplished by 15 mechanism hereinafter to be described, lower case type are diverted into the lower case assorting channel, and upper case type into the upper case assorting channel, which continue down the distributing column. 20 The distributing column is made up primarily of the vertically extending bar members 91, 92 and 94. These members are spaced apart from front to rear of the machine, and are grooved transversely to provide 25 seats 95 for the assorting pallets 96. The assembly of the assorting pallets 96 with the bar members 91, 92 and 94, divides the space intermediate the bar members into a series of relatively vertically disposed stages. 30 There is a pallet, and hence a stage, for each type character which the machine is designed to handle, and into each stage intermediate the juxtaposed pallets extends a pair of type guides 97. 35 Each pallet, as will be understood by reference to Fig. 10, includes a horizontally disposed plate member which is pierced with an aperture 96^a which terminates at one end at a guide member 96^b and at the other end 40 in a pair of slots 96^c separated by a receiving tongue 96^d and a pressing member 96^e. The guide member 96^b and pressing member 96^e are spaced apart longitudinally of the pallet a distance equal to the width of the 45 type channel, viz., a distance slightly in excess of the width of a type, and when the pallets are in normal position in the assorting column, the guide members 96^b form the left hand wall of the type channel, and the pressing members 96^e form the right 50 hand wall thereof. The front and rear walls of the type channels are formed by the strips 98 which are inserted through the apertures 96^a and behind the extremities of the guides 97, as will be understood by reference to 55 Fig. 9. These strips 98 cross the seats 95, and aline with the slots 96^c of the pallets. At the right hand extremities of the guides 97 are arranged turning members 99, which 60 substantially form continuations of said guides, but are turned through an angle of 90° from the horizontal toward the front of the machine. When the pallets 96 are in normal position, the apertures 96^a are in

alignment vertically, so that an uninterrupted channel is provided for the passage of type downwardly from the switching member 90. However, a type in its progress down this channel may be stopped in any stage opposite a pair of the guides 97, by the retraction of the associated assorting pallet leftwardly to the position of the lowermost pallet illustrated in Fig. 8. In this position the pressing member 96^e is drawn to the left of the type channel, and the receiving tongue 96^d is interposed across the channel to receive the falling type. The type falls with its base upon this receiving tongue 96^d, and is held upright by the pressing member 96^e which engages its right side, the strips 98 which engage its top and bottom, and the extremities of the guides 97 which engage its left side. In this position, the top and bottom grooves of the type are alined with the guides 97, and when the pallet 96 is released so as to resume its normal position, which it does under spring pressure, the type will be pushed onto the guides 97 by the pressure from the pressing member 96^e. 90

The arrangement of the outer extremities of the turning members 99 is such that they will register with the type-receiving channels of the type magazine 9, when the latter is disposed in a vertical position at the right hand side of the machine, and the connections of the assorting pallets 96 to the keys in the keyboard correspond to the order of the keyboard connections to the type setting mechanism described in the aforementioned application so that the type will be assorted, by operation of the keyboard, into the same several magazine compartments that it is dispensed from in the setting operation. 100 105

The mechanism for selectively operating the assorting pallets and the case switching member will be understood by reference to Figs. 1, 3, 4, 7 and 8.

It has been explained above how the manually manipulative keys 4 together with their levers, are carried in a slidable frame 2 which may be adjusted longitudinally of the machine frame. Each key lever has a depending arm 26 which is arranged to cooperate selectively with a setting bell crank lever 27 or a distributing bell crank lever 28. There is a series of each sort of these levers, the setting levers, whose operation is described in the aforementioned application, being pivoted on a rod 29 extending transversely of the machine, and the distributing levers being pivoted on a rod 30 similarly arranged in the machine in front of the rod 29. 110 115 120 125

Referring to Fig. 1, it will be understood that when the keyboard frame 2 is in the distributing position, i. e., the forward posi-

tion, which is shown in full lines in that figure, the depending arms 26 of the key bars are disposed for coöperation with the distributing bell cranks 28. From each distributing bell crank 28, a connecting rod 100 forms a means of operative connection with an upper case distributing bell crank 101 or a lower case distributing bell crank 102, a series of the former being pivoted on a rod 104, and a series of the latter being pivotally supported on a rod 105. The operative connection between each upper case distributing bell crank 101 and its associated connecting rod 100, is by means of the laterally extending pin 107 on the former and the abutment 108 on the latter adapted to engage the pin. Similarly, the operative connection between the rod 100 and the associated lower case bell crank 102, is by virtue of a laterally extending pin 109 carried by the bell crank, and abutment 110 on the rod. When the rod 100 is in the position illustrated in Fig. 1 with the abutment 110 in operative disposal relative to the pin 109, the lower case bell crank will be operated when the associated distributing bell crank 28 is swung, while, when the rod 100 is lifted to the position illustrated in Fig. 2 with the abutment 108 in operative disposal relative to the pin 107, the upper case distributing bell crank 101 will be operated upon operation of the associated distributing bell crank 28. Each upper case distributing bell crank has a pull rod 111 extending up to suitable connecting members including a pull rod 116, whereby the associated upper case assorting pallet may be retracted by operation of the associated key. Similarly, each lower case bell crank 102 is operably connected with an associated lower case assorting pallet by connections including the pull rods 114 and 116'.

By virtue of this arrangement of parts, whenever a key 4 in the keyboard is operated, the associated distributing bell crank 28 will be swung to operate the case bell crank which may be operatively connected thereto by the rod 100, from which case bell crank the movement will be transmitted through its attached pull rod 111 or 114, as the case may be, and thence through the associated bell lever and pull rod 116, to the associated assorting pallet, to move said pallet to close the type-distributing channel in the manner hereinbefore described. Upon release of the key, the parts are restored to normal position by the spring 117 and spring 118.

The means for shifting the operative connection between a letter key and an upper or lower case distributing bell crank selectively, includes, in the first place, the shift key 4^a (see Fig. 7) which is arranged for coöperation with a distributing shift bell

crank 50', from the weight arm of which extends the connecting rod 119. The latter leads to an arm 120 on a rock shaft 121, which rock shaft in turn carries a pair of arms 122 connected by suitable links or hangers 124 to a guide plate 125 in which the rear ends of the connecting rods 100 are slidably mounted. The guide plate 125 is mounted for vertical sliding movement in guides 126, and when lifted to its upper position by the rotation of rock shaft 121, will lift abutment 110 out of coöperative disposal relative to pin 109, and abutment 108 into coöperative disposal relative to pin 107. Inasmuch as all of the connecting rods 100 are thus shifted when the shift key is depressed, the manipulation of any letter key will effect the operation of an upper case assorting pallet. In normal position of the shift key and guide plate 125, manipulation of a letter key will produce the operation of the associated lower case assorting pallet.

Simultaneously with this shift of operative connections between the letter keys and the upper and lower case assorting devices, is accomplished a shift of the case switching member 90, in order that the selected type may be guided into the proper case channel. This means of operating the switching member 90 will be understood upon reference to Fig. 3.

Carried on rock shaft 121 is an arm 127 to which is connected a pull rod 128 which extends upwardly into operative engagement with bell lever 129. This bell lever has operative connection with the case switching member 90, so that, when rock shaft 121 is rocked by the depression of the shift key, case switching member 90 will be pushed rearwardly to close the lower case channel 89 and open the upper case channel 88, so that the type released by the separating valve will be diverted into the latter.

Upon every operation of a letter key, and likewise of the space key, a type is released from the column or line above the separating valve 86, and allowed to fall through the distributing channel, as above described. The means for operating the separating valve 86 to effect this operation will be understood by reference to Figs. 1 and 8. Referring first to Fig. 1, it will be understood that upon the depression of any letter key, or the space bar, the rock shaft 57 will be rocked, due to the depression of the universal bar 5 by the lever of the key operated. From the arm 59 carried by the rock shaft 57, extends a pull rod 130, which is arranged for operative connection to the lever 131. A rod 132 extends upwardly from the weight arm of lever 131 to another bell crank pivoted adjacent the upper portion of the machine, and a rod 135 extends from the latter bell crank to the separating valve 86. Hence,

whenever universal bar 5 is depressed, said bell cranks will be rocked, and due to the interconnections, the separating valve 86 will be operated to release the lowermost type 5 of the superimposed column.

In the operation of the above described parts for the purpose of distributing type, it will be understood that the printing holder or cylinder is disposed on top of the machine 10 with its right hand end down, and with a line of type in alinement with the groove formed by the guides 85. When this line of type is released from the carrier, it will fall until the lowermost type comes into engagement with the separating valve 86. The magazine is disposed at the side of the machine with its left hand end up and with its type-receiving channels in register with the channel at the outer extremities of the turning members 99. The keyboard frame is disposed in its forward position so that the arms 26 are in operative relationship with the distributing bell cranks 28. The operator now proceeds to manipulate the keys one 25 at a time and in the regular order in which the keys would be operated in spelling out the composed matter which is being distributed. The types are released one at a time by the separating valve, guided into 30 the upper or lower case distributing channel, according to the position of the shift key, stopped opposite the guideways leading to the magazine compartment assigned to the particular character, and then moved 35 onto the said guideways and toward the magazine. The feed of subsequent type onto the compartment guideway pushes the type ahead of it into the receiving channel in the magazine, with said type in proper position 40 for a subsequent setting operation in the manner before described.

When the type has been assorted and deposited into the magazine, the channels of the latter are closed to prevent the egress of 45 the type by means of any suitable arrangement, so that the magazine may be removed to be transferred to the setting machine.

It is to be particularly observed that in the operation of the machine, the type is so 50 handled that its face is never brought into contact with any metal part such as would be likely to mar it, all of the manipulation and guiding of the type being accomplished by parts which engage it at its top, bottom, 55 side or foot portions. Furthermore, the mechanism described is designed for rapid and accurate operation, and is always under control of the operator.

While I have shown but a single embodiment of my invention, I am aware that, as hereinafter claimed, the same is susceptible of other embodiments differing in detail and arrangements from that disclosed for the purpose of illustration.

What I claim is:

1. In a machine of the class described, the combination of a plurality of type receiving channels relatively vertically disposed, a distributing column providing a vertical type channel crossing the termini of the type receiving channels, means for disposing type to permit its fall by gravity through said type channel, an assorting device disposed in association with each type receiving channel, a keyboard shiftable from upper case to 70 lower case position, and operating connections from the keys of said keyboard to the assorting devices.

2. In a machine of the class described, the combination of a plurality of type assorting guides relatively vertically disposed, a type channel having communication with the said guides, separating means for disposing type to permit its fall through said channel, assorting means for transferring type from 80 said channel to the assorting guides, and a manually operable device for operating the separating means and the assorting means, said last mentioned device being shiftable 85 from upper case to lower case position.

3. In a device of the class described, the combination of a plurality of type assorting channels relatively vertically disposed, one of said assorting channels being for upper case type and the other channel for lower 95 case type, a vertically extending type channel, means for disposing type to permit its fall through the type channel, key-operated means for delivering the upper and lower case type to the respective assorting channels, and selectively operable means for placing the type assorting channels in communication with the type channel whereby to effect the transfer of type from the latter to the former.

4. In a device of the class described, the combination of a plurality of type assorting channels relatively vertically disposed, a vertically extending type channel associated with said assorting channels, means for disposing type to permit its fall through the type channel, and selectively operative means at each assorting channel for arresting the fall of type, said last mentioned means including a keyboard shiftable from upper 110 case to lower case position.

5. In a device of the class described, the combination of a plurality of type assorting channels, means for disposing a type to permit its fall relative to said channels, and selectively operable means for diverting type into said channels, which last mentioned means includes a keyboard shiftable from upper case to lower case position.

6. In a machine of the class described, supporting means for releasing type one at a time from a composed line, assorting compartments arranged for the reception of type

- and disposed below the separating means, and a keyboard shiftable from upper case to lower case position for controlling the distribution of type into said compartments.
- 5 7. In a device of the class described, the combination of a distributing column having a vertically extending type channel, means for releasing type one at a time to permit their falling through said type channel, key-
10 operated means for operating the upper case type from the lower case type, a plurality of horizontally extending assorting compartments disposed in association with the type channel and arranged to support type in alinement, and an assorting pallet disposed in association with each assorting channel and operable to exchange the type from the type channel to the associated compartment.
- 15 8. In a machine of the class described, the combination of a plurality of assorting type guides, an assorting pallet operatively associated with each guide, said pallets being provided with means for guiding type past
20 the assorting guides, means for disposing type to permit its fall past the assorting guides, and means including a keyboard shiftable from upper case to lower case position for operating said pallets selectively to arrest the falling movement of type.
- 25 9. In a device of the class described, the combination of a distributing column having a vertically extending type channel for the transmission of type by gravity, a plurality of assorting compartments disposed laterally of the type channel for the reception of assorted type in alinement, selectively operable devices for arresting type in its movement through the type channel and disposing it in the compartments, and manually operable keyboard mechanism shiftable from upper case to lower case position for operating said selectively operable devices.
- 30 10. In a machine of the class described, the combination of a distributing column provided with an upper case type channel and a lower case type channel, selectively operable devices for arresting the movement of type in said channels, means for positioning type to permit its fall through said channels, and key-operated mechanism shiftable from upper case to lower case position for directing the type into the upper case channel or the lower case channel.
- 35 11. In a machine of the class described, the combination of a distributing column having an upper case type channel and a lower case type channel, means for positioning type to permit its fall through said channels, a series of assorting devices associated with each of said channels for arresting the movement of type therein, operating mechanism arranged for co-operation selectively with the assorting devices of the up-
40 per case channel or the assorting devices of 65 the lower case channel, a switching device for predetermining the course of type as between the respective channels, and keyboard mechanism for operating the switching device and for rendering the operating mechanism effective selectively upon the assorting devices of the respective channels, said keyboard mechanism being shiftable from upper case position to lower case position.
- 45 12. In a machine of the class described, the combination of means for positioning type to permit its fall by gravity, means for guiding the type during such movement, a series of upper case assorting devices disposed to arrest the movement of type, a 80 series of lower case assorting devices arranged to arrest the movement of type, keyboard mechanism in common for operating the upper case and lower case assorting devices, and means for rendering said keyboard mechanism effective selectively upon the upper case assorting devices or the lower case assorting devices.
- 50 13. In a machine of the class described, the combination of a plurality of type receiving compartments, means for positioning type to permit its fall by gravity past said compartments, means for guiding type during such movement, assorting devices operable to arrest the movement of type, said 95 assorting devices being arranged in an upper case series and a lower case series, and keyboard mechanism operable from upper case to lower case position to predetermine which of said series of assorting devices 100 shall be effective upon the type.
- 55 14. In a machine of the class described, the combination of an upper case series of type compartments, a lower case series of type compartments, type channels associated 105 with said series, means for positioning type to permit its fall through said channels, and keyboard mechanism shiftable from upper case to lower case position for directing type to the upper case channel or the lower 110 case channel selectively.
- 60 15. In a machine of the class described, the combination of a movable upper case assorting member, a movable lower case assorting member, means for guiding type to said members, means for positioning type to permit their movement to said members, and means for selectively predetermining the course of type as between said members, which last mentioned means includes keyboard mechanism shiftable from upper case 115 to lower case position.
- 65 16. In a machine of the class described, the combination of a plurality of selectively operable assorting devices, keyboard mechanism shiftable from upper case to lower case position for operating said assorting devices, and means universally operable by 120

said keyboard mechanism for delivering type to said assorting devices.

17. In a type distributing machine, the combination of a series of selectively operable upper case type assorting devices, a series of selectively operable lower case type assorting devices, a keyboard mechanism effective to operate the assorting devices of

either series, said keyboard mechanism being shiftable from upper case to lower case position, and means operable universally by said keyboard mechanism for delivering type to both series of assorting devices. 10

In testimony whereof I hereunto affix my signature, this 2nd day of April, 1917.

WILBUR C. SMITH.
